UNITED STATES PATENT OFFICE.

HORACE C. McCONNELL, OF ROCK ISLAND, ILLINOIS.

HARNESS-SADDLE.

SPECIFICATION forming part of Letters Patent No. 273,118, dated February 27, 1883.

Application filed November 20, 1882. (Model.)

To all whom it may concern:

Be it known that I, HORACE C. McCONNELL, of Rock Island, in the county of Rock Island, and in the State of Illinois, have invented certain new and useful Improvements in Harness-Saddles; and I do hereby declare that the following is a full, clear, and exact description thereof, reference being had to the accompanying drawings, making a part of this specification, in which—

Figure 1 is a perspective view of the parts of my device separated from each other. Fig. 2 is a like view of the same combined, and Figs. 3 and 4 are respectively sections upon lines *x x* and *z z* of Fig. 2.

Letters of like name and kind refer to like parts in each of the figures.

The design of my invention is to render more simple the connection between the saddle-tree and skirts of a harness-saddle; and to this end said invention consists in the means employed for locking the skirt to or upon the tree, substantially as and for the purpose hereinafter specified.

In the annexed drawings, A represents one of the arms of a saddle-tree, which has any desired general form, and at its lower end is recessed upon its outer face, so as to enable it to receive and contain the upper end of a skirt, B.

Upon the outer face of each flange *a*, which forms one of the sides of the recess of the tree A, is provided a lug, *a'*, which in plan view is straight, and forms an extension merely of said flange, while in side elevation said lug shows a downward and inward inclination of its lower face, as seen in Figs. 1 and 2.

Fitted over the lower end of the saddle-tree A is a bar, C, which has each of its ends *c* extended downward and inward, so as to embrace the top side and inclined bottom of the lug *a'*. Said bar is placed upon the flanges *a* at a point above said lugs *a'*, and then moved downward, when its inward-turned ends *c* are engaged by the latter, and said bar drawn firmly against said flanges until further movement in a downward direction is prevented by friction.

Upon the inner side of the bars C, at its longitudinal center, is a pin, *c'*, which extends rearward, and engages with a corresponding opening, *b*, that is provided in the skirt B, and operates to connect the latter with said bar, and through the same with the saddle-tree A.

To connect the saddle-tree A and skirt B, the latter is placed within the recessed face of the former, and the bar C placed across both of said parts, with its pin *c'* in engagement with the hole *b*, after which said skirt and bar are drawn downward until the latter is so firmly wedged upon the lugs *a'* as to render the connection secure.

To remove the skirt B from the saddle-tree A, it is only necessary to drive the bar C upward until it is sufficiently loose to permit it to be disengaged and removed by the hand of the operator. Additional security may be had, if desired, by passing one or more screws or rivets, E, through the upper end of the skirt B, the saddle-tree A, and into or through a lining placed beneath.

While the construction shown is preferably employed, it will be evident that the inclined lugs may be placed upon the inside of the flanges *a*, in which event the bar C would require no hook-shaped ends *c*, but could be plain and straight.

Having thus fully set forth the nature and merits of my invention, what I claim as new is—

As an improvement in harness, the saddle-tree A, having the recessed outer face and projecting wedge-shaped or inclined side lugs, *a'*, and the bar C, provided with the hooked ends *c* and pin *c'*, in combination with each other, and with the skirt B, having the opening *b*, substantially as and for the purpose specified.

In testimony that I claim the foregoing I have hereunto set my hand this 2d day of November, 1882.

HORACE C. McCONNELL.
